[57] CLAIM

The ornamental design for a platform container with transparent lid, as shown and described.

DESCRIPTION

FIG. 1 is a perspective view of a platform container with transparent lid showing my new design;

FIG. 2 is a top plan view thereof;

FIG. 3 is a front elevational view thereof;

FIG. 4 is a side elevational view thereof;

FIG. 5 is a side elevational view of the other side
thereof;

FIG. 6 is a rear elevational view thereof;

FIG. 7 is a bottom plan view thereof; and,

FIG. 8 is a perspective view of the platform with part resting on the lid. The broken line showing of articles in FIG. 8 is for illustrative purposes only and forms no part of the claimed design.
